Hull, Smith, Brock & West,
Attys.

UNITED STATES PATENT OFFICE.

OWEN THOMAS, OF CLEVELAND, OHIO, ASSIGNOR TO THE HYDRAULIC PRESSED STEEL COMPANY, OF CLEVELAND, OHIO, A CORPORATION OF OHIO.

BUNG FOR BARRELS.

Application filed November 29, 1919. Serial No. 341,377.

To all whom it may concern:

Be it known that I, OWEN THOMAS, a citizen of the United States, residing at Cleveland, in the county of Cuyahoga and State 5 of Ohio, have invented a certain new and useful Improvement in Bungs for Barrels, of which the following is a full, clear, and exact description, reference being had to the accompanying drawings.

10 This invention relates generally to sheet metal barrels and more particularly to a bung for such barrels and also to the method of securing said bung.

One object of the invention is to provide 15 a novel construction of bung which can be connected to the barrel by brazing, and another object of the invention is to provide a bung which can be arranged in connection with a chime thereby permitting the bung 20 to be placed at the end of the barrel, and further permitting two bungs to be employed, one at either end and usable as either a filling or venting bung.

With these, and certain other objects in 25 view, the invention consists in the novel features of construction hereinafter fully described, and the invention consists also in certain steps hereinafter set forth, and then pointed out in the appended claims.

30 In the drawings forming a part of this specification Fig. 1 is a side elevation of a sheet metal barrel provided with bungs constructed in accordance with my invention and connected thereto by my improved 35 method Fig. 2 is an enlarged sectional view of the filling bung and Fig. 3 is an enlarged sectional view of the venting bung.

In carrying out my invention I employ a 40 sheet metal barrel A preferably composed of 2 similar sections united at their meeting edges and each end of the barrel is provided with a sheet metal chime B, constructed and connected to the barrel in the manner described and claimed in my application filed 45 November 29, 1919, Serial No. 341,378.

The filling bung comprises a ring portion C and a plug portion D. The ring portion C is inserted in a circular opening produced in the side of the barrel near the end 50 thereof and the edges of said circular opening are turned inwardly as shown at A' and the inner end of the ring C is spun or peened over this inwardly projecting edge as shown at C'.

55 The opening which receives the ring

member C is placed very close to the end of the barrel and the inner edge B' of the chime ring will contact with the ring member as most clearly shown in Fig. 2 and in connection with the chime ring I employ a 60 spacing plate B² which abut against the chime ring. The outer end of the ring member C of the bung is flanged as shown at C² to overlap the edge of the chime ring and the spacing plate B². Between the 65 chime ring and the inturned edge A' and also between the spacing plate B² and the inturned edge, I interpose a definite quantity of brazing material E which may be in the form of a wire or of a brazing paste 70 molded into ring form.

After the parts have been assembled as thus far described they are subjected to the proper degree of heat which will cause the brazing material to fuse and intimately 75 unite the ring member of the bung, barrel, chime ring and spacing plate.

The ring member of the bung is internally threaded as shown at C³ to receive the threaded portion D³ of the plug member 80 of the bung and it will be noted that this plug member is formed with a central boss D' having a threaded recess D² into which can be screwed a spigot (not shown) which is ordinarily connected to the bung 85 and carried upon the interior of the barrel during transportation.

The plug member of the bung is also provided with a wrench socket D⁴ and into which a wrench is fitted in order to screw 90 the plug into or out of the ring member of the bung.

In Fig. 3 I have shown the vent bung which so far as structural features are concerned is identically the same as the filling 95 bung but is preferably made smaller in size. This vent bung comprises the ring member F and the plug member G which as before stated are of the same general character as the ring and plug C and D and they are 100 united by brazing and also cooperate with the inturned edges of the barrel, chime ring, and spacing plate. The plug member of the filling plug, however, is only provided with a socket recess G' and is not 105 constructed with a spigot receiving recess.

In practice I prefer to place the filling bung near one end of the barrel and the filling and emptying bung at the other end of the barrel and upon the side opposite 110

thereof. This enables the barrel to be arranged in a horizontal position and by opening the venting bung the entire contents of the barrel can be drained therefrom, and in filling the operations can be reversed. The relative positions of the filling and venting bungs materially aid in the quick and easy filling and emptying of the barrel, and the wastage which ordinarily occurs in the filling and emptying operations with the barrel now in common use, is avoided.

Having thus described my invention, what I claim is:

- 15 1. The combination with a sheet metal barrel having an opening, of a bung ring inserted in said opening having an exterior flange, a chime ring arranged upon said barrel and engaging a portion of said bung, and a brazing ring arranged between the barrel and bung and uniting said parts.
- 20 2. The combination with a barrel having an opening, of a chime ring arranged upon said barrel, a bung ring inserted in said barrel opening, a portion of said bung ring engaging the chime ring, brazing material surrounding the bung ring and brazing ma-

terial carried by the chime ring and uniting said parts.

3. The combination with a bung ring 30 having an exterior flange, of a barrel having an opening, the edges of which are pressed inwardly, said bung ring being inserted in said opening and having its inner end turned over said edges, a chime 35 ring with which said bung ring contacts, and brazing material surrounding said bung ring and uniting said parts.

4. The herein described method which consists in providing an opening in a barrel, arranging a chime ring upon said barrel adjacent said opening, inserting a bung ring in said opening and bringing the inner edges into contact with the barrel, and bringing the outer end of said bung ring 45 into engagement with the chime ring, arranging brazing material about the bung ring and between the chime ring and barrel, and subjecting said parts to heat whereby they become brazed together. 50

In testimony whereof I hereunto affix my signature.

OWEN THOMAS.
